UNITED STATES PATENT OFFICE.

WILLIAM LUTHER BARRON, OF NEW YORK, N. Y., ASSIGNOR TO THE SINGER MANUFACTURING COMPANY, A CORPORATION OF NEW JERSEY.

SEWING-MACHINE TAKE-UP.

1,166,037.

Specification of Letters Patent. Patented Dec. 28, 1915.

Application filed March 6, 1913. Serial No. 752,271.

To all whom it may concern:

Be it known that I, WILLIAM L. BARRON, a citizen of the United States, residing at New York, in the county of New York and State of New York, have invented certain new and useful Improvements in Sewing-Machine Take-Ups, of which the following is a specification, reference being had therein to the accompanying drawings.

10 My invention relates to sewing machines and particularly to the take-up, the object being to provide a construction by which the operator is enabled to thread the take-up without the loss of time and the annoyance incident to the usual type of take-up.

The invention will be understood by reference to the accompanying drawings in which—

Figure 1 is an end view of a sewing machine head having my improvement thereon, a part being broken away and certain other parts in section; Fig. 2, a side view of a part of the machine head; Fig. 3, a perspective of my improved take-up; and Fig. 25 4, a perspective of a part of the take-up with a compensator.

Similar reference numerals indicate similar parts in the several views.

For the purpose of illustrating one embodiment and application of my invention I have shown the same in a form adapted for use in connection with a multiple needle machine in which the numeral 1 designates the arm, 2 the face plate, 3 the presser-foot bar, 4 the lifter for presser-foot bar, 5 the needle-bar to which is secured four needles, 6 the driving shaft, and 7 the needle-bar crank on the driving shaft which crank is connected through a link 8 with a stud-clamp 9 on the needle-bar 5 to reciprocate the latter vertically. These parts are of a usual and well known form. The clamp 9 has an extension 9' (Fig. 3) to which the needle-thread take-up is secured.

45 The improved take-up comprises an angular plate 10 the lower part of which is formed with an elongated slot 11 through which a set-screw is passed to permit of the vertical adjustment of the take-up. The 50 lateral extension of plate 10 is substantially U-shaped, the outer or leading-in arm 12 of which is formed with notches or open-ended slots, the notches or slots being of such width and depth as to properly receive and hold 55 the threads. The form shown resembles

that of a comb and has been successfully used in practice, but it is not essential to my invention that such exact open-slotted or toothed form be followed. Across the thread entering side of the take-up, and set 60 a short distance in advance of arm 12, is a controller-arm 13 which acts in conjunction with a rigid finger 23 mounted on the machine head to exert a pull upon the needle-thread as the needles approach their lowermost position, whereby slack in the previously formed needle loops around the needle-blades is drawn upward. The member 13 serves also to retain the threads in place within the slotted arms during the operation of the machine. The other arm 14 of the U-shaped extension, or that forming the direct lateral extension of plate 10, is similarly notched or slotted and serves as a guide for the threads, the notches or slots 75 in the two arms being in substantial alignment. The two arms 12 and 14 also serve as bearings for the thread when the latter is acted upon by the compensator. The latter consists of a lever 18 pivoted on a stud 19 on the inner side of face-plate 2, and is actuated by an arm 20 fixed to the presser-foot bar 3. The arm 20 carries at its outer end a roller-stud 21 which engages the slot 18' in the end of lever 18, shown in 85 Fig. 4. The other end 22 of lever 18 is widened and constitutes the thread-engaging end of the compensator.

Secured to the side of the machine head, and extending laterally therefrom a short 90 distance in advance of and above the guard 13, when the take-up is in its lowermost position, is a finger 23 over which the threads pass when the needles descend. It will be seen that the action of the controller-arm 13 95 will bend the threads over finger 23, the latter acting as a friction device to enable the stitch-setting arm in its downward movement to pull slack from the loose loops around the needle-blades rather than from 100 the source of supply.

In threading up the machine the needles are raised to substantially their highest position with the take-up in the position shown in dotted lines in Fig. 2. The respective threads 24 are carried through tension devices (not shown), under controller-arm 13 and then into the notches or open-ended slots of the take-up arms 12 and 14, then through thread-guide 25 on the needle- 115

clamp 26, and then to the needles. In threading up to start sewing, or when a thread breaks during the sewing, the simplicity and ease of threading through the 5 above described take-up will be obvious. Instead of being required to manipulate the end of the thread to pass it through a small opening in the usual take-up arm, often requiring considerable time owing to the location of the take-up, with the difficulties increased when operating a multiple needle 10 machine because of the presence of other threads, an operator with the present take-up simply inserts the thread under controller-arm 13 and drops it into the proper notch or slot of arms 12 and 14, the free end of the thread being accessible for passing through the needle-eye.

In the operation of a double chain-stitch 20 machine to which the present take-up is shown as attached, the described take-up will perform the functions usual to such devices, that is, in that class of machine the take-up will coöperate with compensator 25 lever 18 to draw off thread from the source of supply when the needles are on the up-stroke near their highest position, and will set the stitch when the needles are on their down-stroke and near their lowermost position, the controller arm 13 serving as the 30 upper bearing for the threads, and the lower walls of the notches or slots in arm 12 serving as the lower bearing for the threads. The compensator also performs its usual and 35 well-known function.

While I have shown the take-up arm 12 as having substantially rectangular slots, the invention is not limited thereto, as the slots may be of different forms provided 40 they are open-ended so as to permit the threads to be laid therein.

Having thus set forth the nature of the invention, what I claim herein is:—

1. A self-threading take-up device comprising a take-up arm and means for adjustably connecting the same to the needle-bar of a sewing machine, said arm being formed with an open slot into which the thread may be laid, a thread-controller-arm 45 substantially parallel with said take-up arm and having an operative face opposed to the

thread-engaging portion of the latter arm, a thread-engaging member adapted to co-operate with the said thread-controller arm, and an operative connection between said 55 thread-controller-arm and the needle-bar.

2. In a sewing machine, the combination with a frame, of a needle-bar mounted in said frame and actuating means therefor, a take-up device comprising a take-up arm 60 formed with an open slot into which the thread may be laid, means for adjustably connecting said arm to the needle-bar, a thread-controller-arm movable with the needle-bar adjacent the take-up arm and having an operative face opposed to the thread-engaging portion of the latter arm, and a finger adjustably mounted on said frame and adapted to coöperate with the thread-controller-arm. 70

3. A self-threading take-up device for sewing machine comprising a plate having a U-shaped extension, both arms of said extension being formed with a series of open slots into which the thread may be laid, a 75 third arm carried by said plate adjacent one of its slotted arms and having an operative face opposed to said slots, and means for connecting said plate to a needle-bar.

4. In a sewing machine, the combination 80 with a frame, a needle-bar mounted in said frame and actuating means therefor, of a take-up device comprising a plate adjustably connected to the needle-bar and having a U-shaped extension, both arms of said extension being formed with a series of open slots into which the threads may be laid, a thread-controller-arm carried by said plate substantially parallel with one of its slotted arms and having a thread-engaging face in 90 opposition to said slots, a finger adjustably mounted upon said frame and adapted to coöperate with said thread-controller-arm, and a pull-off member adapted to engage the threads lying between said slotted arms. 95

In testimony whereof, I have signed my name to this specification, in the presence of two subscribing witnesses.

WILLIAM LUTHER BARRON.
